UNITED STATES PATENT OFFICE.

BERT APPLEBY, OF MILWAUKEE, WISCONSIN, ASSIGNOR TO APPLEBY AUTOMATIC SIGN COMPANY, OF MILWAUKEE, WISCONSIN.

MEANS FOR DISPLAYING CARDS.

1,136,919.

Specification of Letters Patent. Patented Apr. 27, 1915.

Application filed July 27, 1914. Serial No. 853,538.

To all whom it may concern:

Be it known that I, BERT APPLEBY, a citizen of the United States, and resident of Milwaukee, in the county of Milwaukee and State of Wisconsin, have invented certain new and useful Improvements in Means for Displaying Cards; and I do hereby declare that the following is a full, clear, and exact description thereof.

10 My invention has for its primary object to provide a simple, economical and effective card or table display mechanism, the same being designed for showing individual cards bearing advertising matter, which cards are 15 manipulated from a stack or series to change automatically and at predetermined intervals.

With the above object in view the invention consists in certain peculiarities of construction and combination of mechanical elements as set forth hereinafter with reference to the accompanying drawings and subsequently claimed.

In the drawings Figure 1 represents a face view of a card or table display mechanism embodying the features of my invention; Fig. 2, a longitudinal section of the same, the section being indicated by lines 2—2 of Figs. 1, 3 and 4; Figs. 3 and 4, cross-sections 30 of the card display mechanism, the sections being upon planes as indicated by lines 3—3 and 4—4 respectively of Fig. 2, and Fig. 5, a face view of a cabinet containing the table display mechanism.

35 Referring by characters to the drawings, 1 represents the base and 2 the uprights of a rectangular frame. The said uprights carry complementary sets of parallel front and rear guide rails 3, 3', respectively, the same 40 being spaced apart and divided to form upper and lower magazines for corresponding stacks of rectangular cards or tables A, B, respectively. It is obvious that the cards may be of various sizes and made of any 45 material desirable. The space between the front and rear sets of rails is of a width approximately equal to the width of the superimposed stacks of cards plus one card, this arrangement being for the purpose of shifting the cards one at a time from the collecting magazine containing the cards B to the upper or display magazine containing the cards A. The stack of cards are supported in the display magazine by a transversely 55 disposed ledge 4, which ledge inclines rearwardly and the cards held in the collecting magazine are supported by a similar bottom ledge 4', that pitches forwardly, the sets of ledges being secured to the frame uprights 2. The ends of the upper ledge 4, 60 which supports the display stack of cards A, are spaced from the juxtaposed front and rear guide-rails a distance approximating the thickness of a single card, whereby a card-receiving throat is formed in conjunction with the front rail 3 and a card-discharge throat is formed with relation to the rear set of rails. The bottom ledge 4' for supporting the superimposed stack of cards B is in abutting engagement with 65 the front and rear rails to form a complete closure whereby the end edges of all of the cards contained in the collecting magazine are supported. The rear rails 3' have detachable upper sections 3'', which sections 70 may be removed for convenience in assembling the two series of cards and said sections are secured by bolts 5, the heads of the same being adapted to engage keyhole sockets 5' that are formed in the uprights. Positioned at the front of the magazines are a 75 pair of endless display magazine carriers in the form of chain belts 6, the same being carried by upper and lower sprocket wheels 7, 7', respectively, which sprocket-wheels are 80 mounted upon upper and lower driven and drive shafts 8, 8', respectively, the same being journaled in suitable bearings with 85 which the frame uprights are provided. The drive shaft 8' is in back gear connection 90 with a motor C preferably of the electric type, the said back gear connection comprising a worm 9, which worm is mounted upon the motor shaft and in mesh with a worm-wheel 9' that is secured to the drive-shaft, it 95 being understood that this back gear connection between the drive shaft and motor may be proportioned to cause the chain belts constituting the carriers to move at the desired speed. Each of the chain belts 6 100 carry alined feed fingers 10, which fingers, when traveling upward upon the working stretch of the chains, project within the collecting magazine a distance approximating a portion of the thickness of one card. 105

Mounted upon a rock-shaft 11 that is positioned over the driven shaft 8 is a pair of presser feet 12, which presser feet are under spring control by means of a coiled spring 13 that connects the uprights and an arm 110

13' projecting from the rock-shaft. The presser-feet 12 are normally held in alignment with the face of the display of the first or visible card *x* of the series of cards A positioned in the display magazine. As shown, the said feet are held in position in opposition to their spring control by a rotatory cam ear 14 which is mounted upon the driven shaft 8. The hub is held in frictional contact with one face of a juxtaposed sprocket-wheel 7 by a coiled spring 15 which surrounds the shaft and is maintained under compression by a collar 15' that is fast upon said shaft. The cam hub 14 also carries a tappet spur 16, which spur normally projects in the path of travel of the feed finger 10 that is carried by one of the chain belts.

Positioned rearwardly of the collecting magazine is a pair of collecting carriers in the form of chain belts 18, which chain belts are mounted upon upper and lower sprocket wheels 19, 19', respectively, the same being carried by upper and lower shafts 20, 20', respectively. The lower shaft 20 receives its motion from the drive shaft 8' through sprocket-wheels 21, 21', that are mounted upon the drive shaft and the lower shaft 20, respectively, and in belt gear connection. Positioned over the lower shaft 20 is a rock-shaft 22, which rock-shaft carries a pair of presser feet 23, the same being upon a plane in alignment with the rear face of the collecting magazine; movement of these feet is controlled in one direction by a coiled spring 24, which is connected to the juxtaposed frame upright and an arm of the rock-shaft 22. A tail-piece 23' of one of the feet 23 is arranged to engage a cam ear 25 that projects from a rotatory hub 25', which hub is loosely mounted upon the shaft 20 and is held in frictional engagement with the face of the juxtaposed sprocket-wheel 19' by a coiled spring 26 that is confined by a collar, which collar is secured to the sprocket-carrying shaft 20. The cam hub 25 is also provided with a feed finger 27 that is arranged to be engaged by a feed finger 18', the same being one of a companion pair that are carried by the collecting carriers or chain belts 18. Hence it will be observed that the front display carriers and the rear or collecting carriers comprising the chain belts and their associated presser foot controlling mechanisms are similar in construction, the only difference being that the working stretches of the display carrier mechanism travels upwardly, while the working stretch of the collecting carriers travel downwardly.

60 By referring especially to Fig. 2, the operation of the mechanism is as follows: The working stretch of the display carriers, in traveling upward, will cause the feed fingers 10 to engage the bottom edge of the first card in the collecting magazine. This

card will be caused thereby to travel upward and in front of the card previously displayed. Prior to the first card in the collecting magazine being shifted to the display magazine the presser feet 11 receive an inward kicking impulse through the engagement of the cam ear 14 with the face of one of the presser feet in opposition to its spring control, whereby the entire stack of cards A in the display magazine are pushed backward in order that the entrance throat of said display magazine may be cleared, this action of the presser foot being hereinafter more clearly described. After the card *x* has been completely shifted to its position of display in the upper or display magazine, the feed finger 10 will engage the tappet spur 16 and, as the chain travels over the sprocket 7 the cam hub 14' will be caused to rotate with said sprocket-wheel. Hence, as the cam ear 14 engages the straight lower surface of the foot 11, said foot will be momentarily forced inwardly and thus the entire stack of cards A will be pushed back. The rear card *y* of the series A will hence be forced clear of the retaining ledge 4 in opposition to a pair of very delicate leaf springs 28 with which the rail sections 3' are provided. These springs only serve to hold the last card *y* upon the ledge 4' momentarily and their pressure is not sufficient to prevent the last card from dropping by gravity after it has been shifted backward. Hence the card *y* now starts to drop downwardly into the collecting magazine. In the meantime, before the rear card *y* is positioned to drop, the feed fingers 18' in connection with the collecting carriers are so timed that they assume a position directly under the lower edge of the card *y*, in coming to which position they wipe the rear face of said card.

It should be understood that these cards are of such weight that they will readily drop and hence, as the card *y* falls downwardly it will engage the feet 18', which will now travel downwardly in connection with the working stretch of the chains and thus permit the rear card *y* to settle slowly into nested alignment with the stack of cards B in the collecting magazine, the card *y* being now the rear card of said stack. Previous to the card *y* being introduced into the collecting stack the cam-controlled presser foot 23 will impart a forward movement to the entire stack of cards B, whereby a space is formed at their rear for receiving the card *y* and, incidentally, the front or facing card *z* of the series B will be pushed forward in the magazine to a position where it will be engaged by the feed finger 10 of the display carrier mechanism and lifted by said finger to a position of display similar to that described in connection with the front card *x*.

It is manifest from the foregoing descrip-

tion that the cards are shifted successively and a card will be displayed at the end of each complete cycle of the series. Hence it is obvious that a number of advertising 5 tables or cards can be economically and automatically displayed by manipulating the same from one stack to the other in the manner set forth. It is also within the scope 10 of my invention to employ other visible signals such as lights or bells in order to attract attention to the advertising matter displayed.

While I have shown and described a machine for displaying tables or cards especially for advertising purposes, it is obviously within the scope of my invention to use the machine as a signal device or indicator for streets or for analogous purposes.

I claim:

- 20 1. A machine for displaying tables comprising upper and lower magazines having bottom supports inclined in opposite directions, an endless carrier mechanism positioned at the front of one of the magazines, a similar 25 endless carrier mechanism positioned at the rear of said magazine, means in connection with the carriers for engaging the outer tables contained in each magazine, and a cam-actuated mechanism for laterally shifting the stacks of tables in opposite directions.
- 30 2. A machine for displaying tables comprising upper and lower magazines having bottom supports inclined in opposite directions adapted to receive separate stacks of 35 tables, the bottom support of the upper magazine being arranged to form a throat in

communication with the lower magazine, sprocket carried chain belts mounted upon opposite faces of the lower magazine, a motor for driving the chain belts, a finger carried by each chain belt for engagement with the opposite outer tables of each magazine, spring-controlled presser feet for laterally shifting the stacks of tables in opposite directions, actuating cams for the feet, and means carried by the cams for engagement with the chain belts.

3. A machine for displaying tables comprising upper and lower magazines having bottom supports inclined in opposite directions adapted to receive separate stacks of tables, the bottom support of the upper magazine being arranged to form a throat in communication with the lower magazine, paired endless carriers mounted upon opposite faces of the magazines, a motor for driving the pairs of carriers, fingers carried by each pair of carriers for engagement with the opposite outer tables of each magazine, 50 presser feet for laterally shifting the stacks of tables in opposite directions, actuating means for the feet, and means carried by the feet actuating means for engagement with the aforesaid carriers.

In testimony that I claim the foregoing I have hereunto set my hand at Milwaukee in the county of Milwaukee and State of Wisconsin in the presence of two witnesses.

BERT APPLEBY.
